UNITED STATES PATENT OFFICE

ARTHUR BATES AND FRED RICKS, OF LEICESTER, ENGLAND, ASSIGNEES TO UNITED SHOE MACHINERY CORPORATION, OF PATERSON, NEW JERSEY, A CORPORATION OF NEW JERSEY

ATTACHMENT OF BINDING AND LIKE STRIPS TO ARTICLES

Application filed May 12, 1925, Serial No. 29,735, and in Great Britain June 25, 1924.

This invention relates to the application of binding and like strips to articles, and is particularly concerned with the production of suitcases, bags and the like having what are commonly known as leather bound edges, an important object of the invention being to provide means whereby an binding of leather or the like may be applied and the abutting edges of the sheet material comprising the article secured together simultaneously by a single machine seam of sewing.

The invention is intended primarily to facilitate the production of work of the above character in which the binding strip is applied on the outside of the angle formed by the abutting edges of the material and requires to be fastened on both sides of the angle. Certain features of the invention, however, may be utilized in the production of work in which the binding strip is applied otherwise than to an external angle. Also certain features of the invention may be utilized in the production of work in which the strip is secured at one side only of the angle.

In the specification of British Letters Patent No. 174,419 and No. 198,430 and in the pending United States application of the present applicant, Ricks, and Reginald B. Woodcock, Serial No. 717,769, filed June 4, 1924, there are described inter alia internal and external supports adapted for sewing bag edges, and a convenient construction according to the invention from which the above and other objects and features of the invention will become apparent will now be described by way of example with reference to the accompanying drawings as applied to a sewing machine fitted with work supporting devices of the general nature shown in those specifications.

In the drawings Fig. 1 is a front view of an external work support provided with binding strip guides and strip notching gages; Fig. 2 is a section on line 2—2 of Fig. 1; Fig. 3 is a plan view looking in the direction of the arrow in Fig. 2; and Fig. 4 is a perspective view of a portion of an article of work after attachment of a binding strip. As shown by Fig. 2, the upper and lower

surfaces 3 and 4 of the external support for the article are at right angles to one another, being adapted for bag, suitcase and similar work and are adjustably fixed to a stitching machine in the same way as the support 28 shown in specification No. 198,430 above referred to. The surfaces 3 and 4 support adjacent faces of the article at an inclination to and intersecting the needle path. The work is fed from the right to the left of Fig. 1, and mounted just to the right of the sewing point upon the upper and lower surfaces 3 and 4 are two strip guiding members 6 and 7 between which and the surfaces 3 and 4 a strip is guided in position properly to overlie the edge of the work. The surfaces 3 and 4 at the right hand side of the sewing point are set back to an extent which brings the inside face of the strip guiding members 6 and 7 approximately in alignment with the portions 8 and 9 of the surfaces 3 and 4 adjacent to the sewing point so that up to the sewing point the strip is maintained out of contact with and behind the body of the suitcase or

similar article of work. The strip is primarily guided towards correct attaching position by a guide composed of a rear plate 10 mounted on the machine frame and front plate 12 secured to the rear plate by screws 13. This guideway formed by the plates 10 and 12 is provided with a V notch on its upper side, which notch is for the purpose of allowing a V-shaped piece to be cut out of the strip where it passes round a corner of the work, as shown in Fig. 4. In sewing along an edge of the work, the operator will stop the machine when an oncoming corner of the work is opposite the bottom of the notch and by means of a hand knife cut out the portion of the strip within the notch.

When a corner of the work is being sewn, as described in specification No. 198,430, that portion of the strip which overlies the actual corner of the sheet 15 about which the other sheet 16 is bent will close up as indicated by the line 17, and produce a flat uncreased surface of the strip at this point. At the angle of the notch blocks 30 of fibre or like material are removably fixed to avoid blunting

of the cutting knife employed. The guiding members 6 and 7 are conveniently held, as shown, on to the external support by screws 18 and spiral springs 19 which press the members 6 and 7 outwardly from the angle of the support to the limits determined by adjustment of the screws. This arrangement facilitates insertion of the leading end of each fresh strip used. The screws 18 may be adjusted either for strips of different widths or to permit one side of the bent strip to overlie the edge of the work further than the other as may sometimes be required.

The extreme right hand edge of the external support is flared away backwardly at 21 to ensure free passage of the strip from the notched guide. This guide is set farther back than and at a small horizontal angle to the line of junction of the surfaces 3, 4 so as to be entirely clear of the work as the sewing is progressing.

The apertures in the external support for the passage of the needle and awl should be arranged to support the work as closely as possible to the needle and awl; in particular the aperture in the surface 3 should have its lower edge positioned so that the awl only just clears it, the work being thereby supported close to the point at which the awl emerges after penetrating the work, and in consequence preventing any tendency of the awl to push the strip into the aperture, such tendency being most apparent, in the absence of close support, just when a notched portion of the strip is being sewn at a corner of the article. Preferably a slotted plate 22 is provided to cover the needle hole in the surface 3 and support the work close to the point at which the awl emerges after penetration. This plate is secured to the upstanding rib of the work support by a screw 23 which passes through a slot in the bent-over end of the plate. The forward end of the plate ends in a tang, or stem, 24 which is bent rearwardly from the body of the plate so as to enter an inclined slot cut in the rib. This arrangement allows of highthwise adjustment of the plate to centralize the line of action of the needle in the slot.

To the left hand side of the sewing point the surface 3 may be set back as shown at 26 and reduced in height as shown to facilitate the maneuvering of the work in such manner that close pressure thereof against the external support is obtained at the sewing point.

The surface 4 of the work support is provided with a shallow groove 25 which extends on either side of the awl hole. This groove enables the operator to feel when the corner 60 of the bag has reached the sewing point and forms a pivot within which a corner of the bag seats when the latter is turned to present the next side to the sewing instrumentalities.

As above indicated, the notching of a binding strip may quite conveniently be done by a

hand knife when the necessary gauging surfaces are provided on the machine. However definitely positioned cutting means such as a V-shaped knife adapted to move transversely across the notched guide under the actuation of a handle, treadle or machine operated cam or the like may be provided.

It will also be apparent that notching may be employed when the article to which a strip is being applied has for example curved edges or is otherwise of shape such that the lengths of the two edges of the strip when attached require to be different to conform properly to the article.

The invention having been thus described, what is claimed is:

1. In a machine for sewing bags or like articles, means for supporting the work with adjacent faces at an inclination to and intersecting the needle path, and means for guiding an edge binding strip across the needle path in position to be sewed to both of said faces.

2. In a machine for use in the manufacture of bags or like articles, the combination with means for guiding and securing an edge binding strip about the angle at the abutting edges of the angularly disposed sheets of material forming adjacent faces of the article of devices for use in notching the strip on its passage to the attaching point.

3. A method of attaching an edge binding strip about the angle formed by adjacent faces of a bag or like article which comprises feeding the bag and strip past the attaching point and forming notches in the strip on its passage to the attaching point, extending from one edge across that portion of the strip which is to be applied to one of said faces.

4. In a machine adapted for attaching strips to the edges of angular articles, means for guiding the strip towards the securing point provided with surfaces defining a portion of the strip which requires to be removed before attachment.

5. In a machine for sewing bags or like articles, the combination with a work support arranged to support the work with adjacent faces at an inclination to and intersecting the needle path and provided with a needle hole of a plate covering the needle hole and provided with a slot registering with the hole.

6. In a machine for sewing bags or like articles, the combination with a work support arranged to support the work with adjacent faces at an inclination to and intersecting the needle path and provided with a needle hole of a plate adjustable on the work support transversely of the direction of feed, said plate covering the needle hole and provided with a slot registering with the hole.

7. In a machine for securing the edges of bags or like articles, the combination with a work support provided with surfaces for

- supporting the angularly disposed sheets of material forming adjacent faces of the article with their edges abutting as said articles are fed past the securing means during the operation, of means for guiding an edge binding strip to the securing means in position to be attached to the angle formed by said faces whereby the edge binding strip is attached to the article by the same means which secure the edges of the article together.
8. In a machine for securing the edges of bags or like articles, the combination with a work support provided with work supporting surfaces substantially at right angles to each other over which the angularly disposed sheets of material forming adjacent faces of the article are fed past the securing means during the securing operation, of guides arranged to direct an edge binding strip in bent condition to the securing means as the article is fed past the securing means whereby the edge binding strip is attached to the article by the securing means by which the edges of the article are secured together.
